UNITED STATES PATENT OFFICE.

JOSIAH A. DEWEY, OF SAN FRANCISCO, CALIFORNIA, ASSIGNEE, BY DIRECT AND
MESNE ASSIGNMENTS, TO MURPHY WALL BED CO., OF SAN FRANCISCO, CALIFORNIA,
A CORPORATION OF CALIFORNIA.

FOLDING BED.

1,233,759.

Specification of Letters Patent. Patented July 17, 1917.

Application filed April 29, 1913. Serial No. 764,328.

To all whom it may concern:

Be it known that I, JOSIAH A. DEWEY, a citizen of the United States, and a resident of the city and county of San Francisco and State of California, have invented certain new and useful Improvements in Folding Beds, of which the following is a specification.

The invention relates to folding beds which are adapted to be moved from a horizontal to a vertical position and vice versa.

The object of the invention is to provide a folding bed which in the vertical position lies close to the wall or in a recess and which in a horizontal position is spaced from the wall or moved out of the recess.

Another object of the invention is to provide a cheap and simple folding bed in which the counterbalancing effect of the counter-weight is substantially constant.

The invention possesses other advantageous features, which, with the foregoing, will be set forth at length in the following description where I shall outline in full that form of the invention which I have selected for illustration in the drawings accompanying and forming part of the present specification. The novelty of the invention will be included in the claims succeeding said description. From this it will be apparent that I do not limit myself to the showing made by said drawings and description as I may adopt many variations within the scope of my invention as expressed in said claims.

Referring to said drawings:

Figure 1 is a vertical section of the bed in the horizontal position, part of the bed frame being broken away to reduce the size of the figure.

Fig. 2 is a similar view of the bed in the vertical or folded position.

Fig. 3 is a similar view of a portion of the bed showing the position the parts assume as the bed is being moved from the horizontal to the vertical position.

Fig. 4 is a similar view of a portion of the bed showing the position that the parts assume as the bed is being lowered from the vertical to the horizontal position.

Fig. 5 is a detail view of one of the slides on which the bed frame is mounted.

Fig. 6 is a cross section taken on the line A—A Fig. 5.

Fig. 7 is a cross section taken on the line B—B Fig. 5.

Folding beds are usually arranged in a recess or wardrobe so that when they are in the folded or vertical position they may be concealed, and it is desirable that when folded they lie as close as possible to the rear wall of the recess or wardrobe so that the recess or wardrobe may be shallow. It is desirable also, however, that when the bed is in the horizontal position, that the head of the bed be removed from the rear wall since persons have an aversion to sleeping with their heads in the recess or wardrobe. The present bed is designed to produce these two desirable results.

The device comprises a bed frame 2 provided at the foot with the pivoted legs 3 and the foot board 4. At the head end of the bed frame is arranged a fixed head frame 5 of sufficient height to accommodate the pillows and bedding, to which is pivoted or coupled the foldable head frame or top frame 6. The bed frame is pivoted adjacent the head end at 12 to the slides 7 which are arranged on the frames or structures 8, arranged on opposite sides of the head of the bed. The frames 8 are mounted on the floor, wall or other structure on which the bed is supported, and when the bed is to be folded into a recess, may lie within the recess. The slides 7 are preferably provided on their inner ends with rollers 9 which engage the tracks 11—12 fixed on the structures 8 and bear on the rollers 13 mounted on the structures 8, so that they readily slide in and out as the bed frame is moved from one position to the other.

Fixed to the bed frame and projecting from the sides thereof is a horizontal bar or rod 14, which, in the opening movement of the bed, engages the structures 8, to cause the slides 7 to move forward, thereby moving the bed frame out of the recess or away from the wall. Fixed to the structures 8 below the position occupied by the bar 14 when the bedframe is in a vertical position, is a cross bar 15, which is engaged by the bed frame as the bed is being closed, thereby stopping the forward movement of that part of the bed frame occurring between the head of the bed and its point of support and causing a further closing movement of the bed to

move the slides 7 backward, so that the bed in the closed position lies close to the wall or in the recess. When the recess construction is employed, a panel 16 is preferably 5 provided on the bottom of the bed frame, so that when the bed is closed, the panel closes the recess and conceals the bed. When the panel construction is employed, the lower edge of the panel, as the bed is 10 being opened, engages the front faces of structures 8, and performs the function of the bar 14 so that in such panel construction the bar 14 may be omitted. Also when the recess construction is employed, the lower 15 portion of the recess is closed by a fixed base-board 17, secured to the structures 8 or to the wall on opposite sides of the recess, and the upper edge of the base board may serve the purpose of the bar 15, or the bar 20 may be retained for the purpose of reinforcing the upper edge of the base-board.

The means for counterbalancing the weight of the bed as it is being moved, consists preferably of a counterweight 18 arranged on the top frame 6, so that the counterbalancing effect thereof is effective at the upper end of the fixed head 5. The horizontal distance between the pivotal point of support of the bed frame and the 25 top of the fixed head is always of appreciable value and does not vary greatly, so that the counterbalancing effect of the counterweight is continuous and almost constant. The top frame 6 is guided at its 30 upper end by the outwardly inclined guides 19 fixed to the structures 8, which are engaged by lugs or pins 21 on the top frame. The inclined guides are arranged so that

when the bed frame is in the horizontal position, the top frame is in a vertical position 40 and aligned with the fixed head frame. The top frame is brought forward, as the bed frame is pulled downward, and it is moved backward, as the bed frame is folded upward. 45

I claim:

1. A folding bed comprising a bed frame adapted to be moved through a vertical arc, slides upon which said frame is pivoted, a fixed head on said frame, a foldable head 50 connected to said fixed head, means for moving said slides as the bed frame is moved through said arc and means for transversely moving said foldable head as the frame is moved through said arc. 55

2. A folding bed comprising a rigid bed frame, supporting structures arranged on opposite sides of said frame, slides supported by said structures to which the frame is pivoted, means attached to said frame arranged to engage said structures as the frame is moved from a vertical to a horizontal position to move said slides forward and independent means attached to said structures arranged to be engaged by said frame as the frame is moved from a horizontal to a vertical position to move said slides backward. 60

In testimony whereof, I have hereunto set my hand at San Francisco, California, 70 this 23rd day of April, 1913.

JOSIAH A. DEWEY.

In presence of—

H. G. PROST,
P. S. PIDUREE.
